UNITED STATES PATENT OFFICE

SAMUEL G. GREEN, OF GRAY, GEORGIA

RECOIL MOUNT FOR GUNS

Application filed April 21, 1927. Serial No. 185,584.

(GRANTED UNDER THE ACT OF MARCH 3, 1883, AS AMENDED APRIL 30, 1928; 370 O. G. 757)

The invention described herein may be manufactured and used by or for the Government for governmental purposes without the payment to me of any royalty thereon.

5 The subject of this invention is a recoil mount for guns.

The principal object of the invention is to provide a mount for rapid fire guns in which a recoiling cradle carrying the rigid frame 10 of the gun is so arranged with respect to its support as to provide favorable operating conditions.

With the foregoing and other objects in view, my invention resides in the novel arrangement and combination of parts and in the details of construction hereinafter described and claimed, it being understood that changes in the precise embodiment of the invention herein disclosed may be made within 20 the scope of what is claimed without departing from the spirit of the invention.

A practical embodiment of the invention is illustrated in the accompany drawing, wherein:

25 Fig. 1 is a plan view, with parts in section, of the improved mount;

Fig. 2 is a view in side elevation;

Figs. 3 and 4 are respectively plan and side elevational views of the outer cradle;

30 Figs. 5 and 6 are detail sectional views on their respective lines of Figs. 1 and 2.

Referring to Figs. 1 and 2 there is shown a bifurcated standard 5 and a cradle or supporting frame 6 which conform in design and 35 dimension to the corresponding units disclosed in my copending application Serial No. 61,613, filed October 9, 1925, and arranged to directly mount either a .30 or .50 caliber machine gun.

40 The standard is to be supported in the usual manner for 360° rotation in azimuth and in its upper extremity receives the trunnions 7 whereby the cradle is mounted for movement in elevation.

45 The cradle consists of a pair of plates 6^a spaced at the rear by a bolt 8 and at the front by a block 9 formed with wide grooves 9^a in its upper and lower faces. Within the outer cradle 6 is placed a recoiling cradle 10 like-

50 wise consisting of spaced plates 10^a connected

at their forward end by a cross head 11 having a transverse recess 12 for straddling the narrow spacing block 9 on which it bears. The recoil cradle is additionally supported for reciprocal movement with respect to the 55 outer cradle by means of a pair of guide rods 13 extending through apertures in the cross head 11 and block 9 and by means of a rear bearing consisting of a bolt 14 carried by the outer cradle and inserted in slots 15 in the 60 rear of the cradle plates 10^a.

Interposed between the blocks 9 and the inner walls of the cross head 12 are a number of springs mounted on the guide rods 13, the forward group of springs 16 serving to restrain the cradle 10 in recoil and being thus energized to restore it to battery against the action of the rear group buffer springs 17. Adjustment of the springs to suit varying 70 loads is effected by means of the plugs 18 threaded in the cross head 11 and establishing seats for the forward group of springs. A plate 19 may be attached to the under side of the cross head to establish friction between the sliding members and by fitting in the 75 grooved face of the block 9 prevents lateral displacement of the recoil cradle.

The recoil cradle is designed to mount a standard machine gun of either .30 or .50 caliber and to this end there are provided in 80 the recoil cradle plates alined sets of apertures 20, 21 and 22, the first two serving to receive the attaching pins when mounting the .30 caliber guns and the first and last receiving the pins when mounting the .50 caliber 85 gun. One of the cradle plates is also provided with sets of apertures 23 whereby different sized brackets 24 which carry the ammunition boxes may be alternately attached.

The particular arrangement of the various 90 elements and the relationship they bear each other are designed to produce a stable mount under all conditions of operation.

With these considerations in view the cradle trunnions 7 are located on the center line 95 of the gun reaction transmitted to the outer cradle in firing and in obtaining these conditions the forward attachment of the guns to the recoiling cradle are situated in front of the trunnions.

The point of application of the thrust of the recoiling cradle to the outer cradle is forwardly and below the cradle trunnions substantially in line with the center of gravity of the gun and cradle assembly and forms the shortest practical lever arm acting along the center line of the recoiling cradle whereby it produces a tendency to elevate the rear end of the gun which tendency is offset by the natural inclination of the gunner to bear down on the stock of the gun.

The axis of the bearing surfaces of the recoiling cradle is inclined with respect to the line of application of thrust to the recoiling cradle, which line is determined by the forward and rear attachments of the gun. The purpose of this inclination is to set up sufficient friction to compensate for gravitational forces influencing the recoilable cradle at the higher angles of elevation and to dampen the springs to prevent free rebound so that the gun is fully in battery before the next shot is fired. The friction component thus introduced during recoil of the cradle will be absent during counter recoil as the restoring force is exerted along the axis of the bearing.

I claim:

1. A gun mount embodying a standard, an outer cradle trunnioned in the standard and including a pair of plates and a grooved spacing block forwardly of the trunnions, an inner cradle including spaced plates having means for mounting guns of different caliber, a cross head at the forward end of the inner cradle arranged to straddle and bear on the spacing block, guide rods in the cross head and space blocks, springs encircling the guide rods and seated on the cross head and spacing block, means for adjusting the tension of the springs and a sliding connection between the rear ends of the inner and outer cradles.

2. A gun mount embodying a standard, an outer cradle trunnioned in the standard and including a pair of plates and a grooved spacing block forwardly of the trunnions, an inner cradle including spaced plates having means for mounting a gun, a cross head at the forward end of the inner cradle arranged to straddle and bear on the spacing block, guide rods in the cross head and spacing block, springs encircling the guide rods and seated on the cross head and spacing block and a sliding connection between the rear ends of the inner and outer cradles.

3. A gun mount embodying a standard, an outer cradle trunnioned in the standard and including a pair of plates and a grooved spacing block forwardly of the trunnions, an inner cradle including spaced plates having means for mounting a gun, a cross head at the forward end of the inner cradle arranged to straddle and bear on the spacing block, means for securing the cross head against vertical

displacement with respect to the spacing block, springs seated on the cross head and spacing block and a sliding connection between the rear ends of the inner and outer cradles.

4. A gun cradle embodying a standard, an outer cradle trunnioned in the standard and including a pair of plates and a grooved spacing block forwardly of the trunnions, an inner cradle including spaced plates having means for mounting a gun, a cross head at the forward end of the inner cradle arranged to straddle and bear on the spacing block, springs seated on the cross head and spacing block and a sliding connection between the rear ends of the inner and outer cradles.

5. A gun mount embodying a standard, an outer cradle trunnioned in the standard and including plates and a spacing block forwardly of the trunnions, an inner cradle including spaced plates and a cross head straddling and bearing on the spacing block, means for restraining the inner cradle on recoil and restoring it to battery, means for buffing the counter-recoiling cradle and a sliding connection between the rear ends of the inner and outer cradles.

6. In a gun mount, a support trunnioned for angular movement, a recoilable cradle having means for attachment of a gun and bearing on the support, the axis of the bearing surfaces being inclined with respect to the line of application of thrust transmitted by the gun to the cradle.
